DENTAL TRAY SUPPORT ARM OR SIMILAR ARTICLE

John M. Gardella, Staten Island, N.Y., assignor to The
S. S. White Dental Mfg. Co., Philadelphia, Pa., a corporation of Pennsylvania

Filed Oct. 29, 1963, Ser. No. 77,201

Term of patent 14 years

(Cl. D24—1)

FIG. 1

FIGURE 1 is a perspective view of a dental tray support arm or similar article, attached to a conventional dental unit, showing my new design;

FIGURE 2 is a side elevational view of a dental tray support arm or similar article;

The broken line showing of the dental unit and related equipment is included for illustrative purposes only.

I claim:

The ornamental design for a dental tray support arm or similar article, as shown and described.
